ARTIFICIAL FISH BAIT

Herman J. Heinrichs, Flint, Mich.

Application May 23, 1949, Serial No. 2,813

Term of patent 14 years

(Cl. D31—4)

To all whom it may concern:

Be it known that I, Herman J. Heinrichs, a citizen of the United States, residing at the city of Flint, in the county of Genesee and State of Michigan, have invented a new, original, and ornamental Design for an Artificial Fish Bait, of which the following is a specification, reference being had to the accompanying drawing, forming part thereof.

Figure 1 is a perspective view of an artificial fish bait, showing my new design.

Figure 2 is a side elevational view thereof, and Figure 3 is a top plan view of the same.

I claim:

The ornamental design for an artificial fish bait, as shown.

HERMAN J. HEINRICHES.
